UNITED STATES PATENT OFFICE.

ULYSSES S. HENDERSON AND ADOLPH F. SCHRAMM, OF COLUMBUS, OHIO, ASSIGNEES
TO THE E. M. HULSE COMPANY, OF COLUMBUS, OHIO, A CORPORATION OF OHIO.

SOFA OR DAVENPORT BED.

1,074,050.

Specification of Letters Patent. Patented Sept. 23, 1913.

Application filed May 19, 1913. Serial No. 768,451.

To all whom it may concern:

Be it known that we, ULYSSES S. HENDERSON and ADOLPH F. SCHRAMM, citizens of the United States, residing at Columbus, in the 5 county of Franklin and State of Ohio, have invented a certain new and useful Improvement in Sofa or Davenport Beds, of which the following is a specification.

This invention relates to such a folding 10 bed or davenport as is shown for example in Letters Patent of the United States, No. 1,061,777, dated May 13, 1913, issued upon the application of William A. Pease, and has for its object to provide improved means 15 for moving the back out of position to interfere with the operation of the seat and bed.

The invention is embodied in the construction herein shown and described, the features of novelty being pointed out in the claims 20 appended hereto.

In the accompanying drawings forming part hereof—Figure 1 is a view in elevation of the end of the structure with the end member or standard removed so as to expose 25 the mechanism. In this view the bed is shown as opened. Fig. 2 is a similar view showing the bed-closed.

As usual in such structure 11 designates the end members or main supporting stands, 30 ards of which there are two, between which is suitably secured and supported the base box or stationary frame 10. To the forward upper corner of the base box or frame 10 is hinged at 12^a the seat frame 12.

The characters 13, 14 and 15 designate respectively the inner, outer and middle sections of the folding bed frame which are operated by suitable devices connected with the seat frame substantially as shown in the 40 patent hereinbefore referred to and require no description herein because they do not constitute an essential part of the present invention.

Pivoted at 22 on the end of the base or 45 frame 10 is a lever 21 having at the extremity of its upper arm a lateral inwardly extending bearing to act on the edge of the seat, said bearing being indicated herein by broken lines at 23 (but shown in detail in 50 said former patent) and said lever also having connected with its lower end one end of

a strong coiled spring 24 that has its other end connected to an eye 25 secured in the rear wall of the base box or frame. When the seat frame is closed the edge of the end 55 of the frame depresses the upper arm of the lever 21 and stretches the spring thereby storing power for actuating said lever to assist in raising the seat when the bed is to be opened all as explained in said former 60 patent.

In the present invention the back 9 is pivoted at its upper part to swing between the ends 11 on an axis at 9^a and is provided at its lower corner with a slotted member 8 65 fixed thereto. Pivoted at 7^a on the end of the box 10 is a lever 7 having at one end a pin at 7^b to engage the slotted member 8, and hinged at the other end at 7^c to one end of an arm 6 pivoted at 6^b on the lever 21. When, 70 therefore, the seat is raised to open the bed the lever 21, being actuated by the spring, draws up the arm 6 and throws down the upper arm of the lever 7 thereby throwing rearward the lower portion of the back and 75 removing it from position to interfere at all with the rising seat. Because of the construction shown the movement of the back is very slight and so as not to be objectionable. Furthermore the seat is held in substantially 80 this rearward position until the seat is nearly closed, it being observed that the operating parts cause only slight movement of the back.

The mechanism described can be and pref- 85 erably will be in all respects the same at each end of the sofa or davenport bed.

We are aware that it is not broadly new to provide means for operating a swinging back by manipulation of a seat, hence we do 90 not broadly claim such.

What we claim is:

1. In a sofa or davenport bed, the combination with a supporting frame having a movable back and a seat frame hinged on 95 said frame adapted to turn outward, a lever having an actuating spring, controlled by the position of the seat, and means connecting said lever and back for causing the back to move rearward when the seat frame is 100 turned outward.

2. In a sofa or davenport bed, the combi-

nation with a supporting frame having a movable back and a seat frame hinged on said frame adapted to turn outward, a lever having an actuating spring controlled by the 5 position of the seat, and means including a link and lever connecting said first mentioned lever and back for causing the back to move rearward when the seat frame is turned outward.

ULYSSES S. HENDERSON.
ADOLPH F. SCHRAMM.
